(No Model.)

A. B. WOOD.

ROTARY STEAM ENGINE.

No. 286,102.

Patented Oct. 2, 1883.

UNITED STATES PATENT OFFICE.

AUGUSTUS B. WOOD, OF FOUNTAIN HILL, ARKANSAS.

ROTARY STEAM-ENGINE.

SPECIFICATION forming part of Letters Patent No. 286,102, dated October 2, 1883.

Application filed May 13, 1882. (No model.)

To all whom it may concern:

Be it known that I, AUGUSTUS B. WOOD, a citizen of the United States, and a resident of Fountain Hill, in the county of Ashley and State of Arkansas, have invented a new and valuable Improvement in Rotary Steam-Engines; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a vertical cross-sectional view of my steam-engine, and Fig. 2 is a side view of same with the one section removed.

This invention has relation to rotary steam-engines; and it consists in the construction and novel arrangement of parts, as will be herein-after fully described, and particularly pointed out in the claims appended.

In the accompanying drawings, the letter A designates the annular piston-chamber in the piston-cylinder B, which is made in two sections, C C', having flanges a, perforated at b for the passage of bolts c, whereby the sections are secured together. Each section is provided with central enlargements, D, around the shaft e, said enlargements being recessed and provided with pillow-blocks or brass bearings g', which are adjustable by means of set-screws h to take up the lost motion of the main shaft, which these bearings support. The main shaft carries the piston-plate or disk-arm E and the eccentric D', whereby the slide-valve F is operated. The disk-arm E is circular, and turns in a narrow circular chamber, g, around the main shaft, which communicates with the annular piston-chamber A. The margin of the disk-arm extends to the piston-chamber, and the piston-head G, which revolves around the annular chamber A, is secured to the edge of the disk E by means of an arm, h', of the disk, which extends through a bearing in the head, and is secured by a nut. The piston-head is provided with packing-rings around its edge, and is made in wedge form, or wider at its outer than at its inner portion, in order that it may wear uniformly. Annular lateral recesses k are made in the walls of the narrow center chamber, g, near

its margin, and in these recesses are placed the packing-rings l, which are kept up to the disk E by means of springs or set-screws and elastic packing.

H indicates a projection from the upper part of the cylinder B, which contains the steam-ports and slideway of the abutment. This slideway m extends transversely across the annular piston-chamber, and sufficiently far 60 into the projection H to form a chamber therein, to receive the abutment when it is moved outward from the piston-chamber. The abutment K is of sufficient size to close the piston-chamber when seated across the same, and is 65 provided with a stem, n, whereby it is connected to a small piston, p, which works in a small chamber, r, in the projection H. In this projection are formed, also, the steam-ports s and the exhaust-port s', extending to the 70 valve-seat.

L indicates the valve-chamber, which is secured to the section C' of the cylinder, and F represents the slide-valve therein, which is connected to the eccentric D' on the main shaft 75 by means of a connecting-rod, N. Small steam-ports z and z' extend to the steam-chamber r of the abutment-piston p, and serve to supply the steam for working the abutment. It may, however, be found advisable to work the abutment by means of a cam on the main shaft, having a connection extending to the stem of the abutment, and operating to move the abutment quickly out of the piston-chamber just 80 before the piston-head passes its seat, and then 85 quickly back into position.

The movement of the engine is simple. The abutment being in position across the piston-chamber, steam entering by one of the steam-ports forces the piston-head to revolve. The 90 steam has full power all the way around the piston-chamber, except for about one-eighth of its length, this space being taken up in the working of the abutment; or the steam may be cut off at three-quarter stroke and the expansion depended on for one-eighth. When the abutment is moved out of the piston-chamber by its cam or by the pressure of steam under its piston, the main piston-head passes its seat, and the abutment is then quickly returned 95 to its position across the piston-chamber.

A reciprocating abutment operated by steam

has been combined with an annular piston-chamber and piston-head prior to my invention. A double saw-tooth packing upon the wheel on the main shaft has been arranged to admit the steam by expanding the saw-tooth rings, thereby forcing them in opposite directions and forming small openings between the faces of the teeth, through which the steam enters.

10 Having described this invention, what I claim, and desire to secure by Letters Patent, is—

15 1. In a rotary engine, the annular piston-chamber A, and the abutment-slideway m and central narrow circular chamber g, communicating therewith, and having the lateral recesses k, packing-rings l, and set-screws, the main shaft e, disk-arm E, piston-head G, and abutment-slide K, substantially as specified.

2. In a rotary engine, the combination, with 20 the piston-chamber and the piston-head revolving therein, of the transverse slideway m and the abutment-slide K, the center chamber, g, its packing-rings l, and the disk-arm E, and the steam-ports s, leading from the piston-chamber to the valve-seat, substantially as specified.

25 3. In a rotary engine, the disk-arm E on the main shaft e and the wedge-form piston-head G, secured to the edge of said disk-arm by the arm h' and nut, substantially as specified.

In testimony that I claim the above I have hereunto subscribed my name in the presence of two witnesses.

AUGUSTUS BALDWIN WOOD.

Witnesses:

W. W. WOOD,
J. F. COBB.
